UNITED STATES PATENT OFFICE.

LOUIS W. GATES, OF WEST HAVEN, CONNECTICUT, ASSIGNOR TO C. COWLES & CO., OF NEW HAVEN, CONNECTICUT, A CORPORATION.

WINDOW-OPERATOR.

1,109,574.

Specification of Letters Patent.

Patented Sept. 1, 1914.

Application filed November 3, 1913. Serial No. 798,927.

To all whom it may concern:

Be it known that I, LOUIS W. GATES, a citizen of the United States, residing at West Haven, in the county of New Haven 5 and State of Connecticut, have invented a new and useful Improvement in Window-Operators; and I do hereby declare the following, when taken in connection with the accompanying drawings and the characters 10 of reference marked thereon, to be a full, clear, and exact description of the same, and which said drawings constitute part of this application, and represent, in—

Figure 1 an outside view of a window 15 operator with the sill and outside trimming removed. Fig. 2 a vertical sectional view of the same. Fig. 3 a view in front elevation of an operating handle and casing in which it is mounted. Fig. 4 a longitudinal sectional view of the same. Fig. 5 a 20 view similar to Fig. 3 with the handle removed. Fig. 6 a similar view with the retaining plate removed, showing the ratchet held against rotation. Fig. 7 a similar view 25 showing the parts free to turn in one direction. Fig. 8 a view in reverse elevation of the casing, showing the idler pulley and sprocket wheel. Fig. 9 a view of the inside of the vehicle door with the inner lining or 30 covering removed, illustrating a modified form of my invention. Fig. 10 a vertical sectional view of the same.

This invention relates to an improvement in window operators, and particularly to 35 means for operating the windows of vehicle doors.

In the more general arrangement of windows a long strap is attached to the bottom of the sash by which the sash may be raised; 40 and unless the sash is raised to the full height and so that the lower edge can be moved forward to rest upon the sill, means must be provided for holding the strap, and in many cases difficulty is experienced in 45 raising the sash by a strap.

The object of this invention is to provide means for raising the sash by the turning of a knob or handle; and the invention consists in the construction hereinafter described and 50 particularly recited in the claims.

In illustrating my invention I have shown the lower part of a vehicle door which may be of any approved design, provided on opposite sides with grooved guides 3, 4, in 55 which the window 5 is guided for vertical

movement into the lower part or pocket of the door. This window may have the usual wood or metal frame inclosing a glass; but as herein shown the glass is not inclosed by a frame but is provided at its lower edge 60 with a metal flange 6 the upper edge of the outer face of which is turned over forming a hook 7, adapted to engage with the upper edge of what I term a fence 8 projecting upward from the sill 9. Connected with the 65 flange 6 and extending downward therefrom is an arm 10 to which one end of a sprocket chain 11 is attached. This chain extends over a sprocket wheel 12, and its other end connected with a cord 13 which passes 70 around an idler pulley 14 at the bottom rail 15 of the door, thence upward through an eye 16 at one side of the arm 10 over an idler pulley 17 in line with the sprocket wheel 12; down around a pulley 18 on a 75 lever 19 and upward to the mid-frame 20 where it is firmly secured. On the cord 13 and secured by a pin 40 is a stop 21 which connects the cord to the arm 10 as it is drawn down, but permits the cord to move slightly 80 upward without moving the arm and allows for taking up any slackness in the cord. The lever 19 is pivotally connected with a bracket 22 at one side of the door and connected with the lever and with the bottom 85 rail 15 is a spring 23 the tendency of which is to pull the lever downward, and hence counterbalance to a certain extent the weight of the window 5. The sprocket wheel 12 is secured to a sprocket wheel hub 24 mounted 90 in a casing 25 secured to the mid-frame 20. Extending through the hub is a shaft 26 to the outer end of which a knob or handle 27 is secured. At its inner end the shaft is formed with radial lugs 28 setting into recesses 29 in the inner face of the sprocket wheel 12. The recesses are wider than the lugs so that a certain amount of independent 95 movement is permitted before the shaft will move the sprocket wheel. Riveted to the hub is a ratchet 30 having double-face teeth 31 and connected with a D shape portion 32 of the shaft is a pawl tripper 33 adapted when turned to lift either of the pawls 34, 35, mounted on the cylindrical portion 36 of the casing 25 to respectively engage opposite faces of the teeth 31. Set into the outer end of the cylindrical portion 36 of the casing 25 is a retaining-plate 37 and secured 105 to this plate is a spring friction yoke 38 the 110

fingers of which embrace a bushing 39 mounted on the D shape portion 32 of the shaft and adapted to turn therewith. The function of the lugs 28 and recesses 29 is to 5 permit the shaft to have a slight movement independent of the ratchet-wheel to allow the tripper to disengage one of the pawls from the ratchet.

When the sash is in the raised position, 10 as shown in Figs. 9 and 10 of the drawings, the lower edge will be engaged with the fence 8 or the lower edge may rest upon the sill 9 in the usual way. In either event it will be necessary to slightly raise the sash 15 so as to release the lower edge and bring it into alignment with the guides 3 and 4. Downward movement, however, will be stopped by the engagement of the pawl 34 with the ratchet 30; but if the handle be 20 turned to the left, the tripper 33 will lift the pawl 34 out of the path of the teeth on the ratchet as seen in Fig. 7 due to the fact that the tripper may have a slight movement independent of the ratchet owing to the provision of the wider recess 29, it being understood that the number of teeth on the tripper correspond to the number of teeth on the ratchet; thus permitting the window to be lowered by turning the handle, the spring 25 23 normally tending to pull the lever 19 downward so that the slack on the cord 13 will be taken up. The moment, however, the handle is released, the ratchet will be caught by the pawls 34 and 35 and further movement arrested. On the other hand, 30 when the sash is down, it may be raised by turning the handle to the right, and in this movement the tripper will raise the pawl 35 so that the ratchet will freely pass the pawl 35. The sash will be locked at all points 35 against movement other than that imparted by turning the handle, and the extent of movement of the lever is only half that of the window. Instead of using a sprocket 40 wheel and chain, the cord 13 may pass over a grooved pulley 41 mounted in the same way as the sprocket wheel 12 and the idlers 14 and 17 may also be omitted as shown in 45 Figs. 9 and 10.

50 I claim:

1. In a window operator, the combination 55 with a vehicle door having a pocket and a mid-frame, a window adapted to be moved up and down in said door, a wheel mounted on said mid-frame, an operating handle adapted to turn said wheel, flexible connections between the door and the window and extending over the wheel into connection with the window, and a balancing lever 60 mounted in the pocket below said window and engaging with said flexible connection.

2. In a window operator, the combination 65 with a casing, of vertical guides arranged on opposite sides, a window adapted to be moved by a chain in said guides, a chain,

a sprocket wheel mounted in said casing and engaging said chain, a ratchet connected with said sprocket wheel, two reversely arranged pawls engaging with said ratchet, a handle, and a tripper connected with the said handle and adapted to lift said pawls. 70

3. In a window operator, the combination with a vehicle door having a mid-frame and a pocket, a window adapted to be moved up and down in said door, a sprocket wheel mounted on said mid-frame, an operating handle adapted to turn said sprocket wheel, and flexible connection between the door and the window and extending over the sprocket wheel into connection with the window and a balancing lever mounted in the said pocket below said window and engaging with said flexible connection. 75 80

4. In a window operator, the combination with a casing, of a window adapted to be moved up and down therein, a sprocket wheel mounted on a shaft in said casing, an operating handle connected with said shaft and adapted to turn said sprocket wheel, and flexible connection between the casing and window and extending over said sprocket wheel, a ratchet connected with said handle, two reversely turned pawls engaging with said ratchet, a tripper adapted to lift the pawls out of engagement with the ratchet, and a friction yoke surrounding 90 95 said shaft.

5. In a window operator, the combination with a casing, of a vertically movable window arranged therein, a sprocket wheel, a shaft extending through said casing upon which the wheel is mounted the end of said shaft formed with projections, and the center of the sprocket wheel formed with recesses wider than said projections whereby the shaft has movement independent of the sprocket, a ratchet connected with the sprocket, two reversely turned pawls adapted to engage with said ratchet, and a tripper adapted to lift the said pawls. 100 105 110

6. In a window operator, the combination with a casing, of a window vertically movable therein, an arm extending downward from said window, a sprocket wheel mounted in said casing, an operating spindle adapted 115 to turn said sprocket wheel, said spindle adapted to have a slight movement independent of the said wheel, a ratchet connected with the sprocket wheel, a tripper connected with the spindle and two pawls 120 adapted to engage the ratchet.

7. In a window operator, the combination with a vehicle door having a mid-frame and a pocket, of a window movable therein, an arm extending downward from said window, a sprocket wheel mounted on said mid-frame, a chain passing over said sprocket wheel and connected at one end with said arm, a cord passing through said arm and attached at one end to the mid-frame and at 125 130

the other end to the free end of said chain, | specification in the presence of two subscr-
a stop adjustably fixed on said cord above | ing witnesses.

said arm and adapted to engage therewith,
and a balancing lever mounted in the said
5 pocket below said window and engaging
with said cord.

In testimony whereof, I have signed this

LOUIS W. GATES.
